Elimir J. Ney, of Lowell, Mass.
Assignor to
The Lowell Manufacturing Company
Letter Patent No. 1542, dated Feb. 28, 1862

The schedule referred to in this Letter Patent and making part of the same.

To all whom it may concern:

Be it known that I, Elimir J. Ney, of Lowell, in the County of Middlesex and State of Massachusetts, have originated and designed a new Pattern for Carpets or other fabrics, of which the following is a full, clear and exact description, reference being had to the accompanying drawings, making part of this Specification.

Corner A. is one fourth of a large star, the interior of which is formed of Key work. When the design is matched a scalloped band 1. surrounds the star and slightly overlaps its points. The interior of the band 1. is filled with small leaves.

Corner B. is one fourth of a large rosette resting on the ground 2. Surrounding this ground is a scalloped border from which radiate small sprigs in lines and dots.

A. band 3. similar to fig. 1. surrounds the figures of corner B. C. at the side is one half of a figure with eight arms, resting on the dotted ground 4. Said ground is surrounded by the frame 5. having projections in the same directions as the arms of fig. C. Two of these projections overlap the bands 1 and 3. and the remaining ones, underlie the frame of Key work D. The corners of the frame D. underlie portions of the bands 1 and 3.

The colors employed for the different portions of the design, may be varied to suit the taste and wish of the manufacturer.

Claim

What I claim as my invention and desire to secure by Letters Patent, is the design or pattern, for Carpets or other fabrics, herein set forth.
